UNITED STATES PATENT OFFICE.

ADOLF FRANKE, OF GROSS-LICHTERFELDE, NEAR BERLIN, AND ERWIN EHRHARDT, OF BERLIN, GERMANY, ASSIGNORS TO SIEMENS & HALSKE, AKTIEN-GESELLSCHAFT, OF BERLIN, GERMANY.

APPARATUS FOR PERFORATING THE TYPE-BANDS FOR AUTOMATIC TELEGRAPH TRANSMITTING APPARATUS OR THE LIKE.

SPECIFICATION forming part of Letters Patent No. 779,153, dated January 3, 1905.

Application filed February 29, 1904. Serial No. 195,955.

To all whom it may concern:

Be it known that we, ADOLF FRANKE, engineer, a subject of the King of Prussia, German Emperor, residing at 23 Sternstrasse, 5 Gross-Lichterfelde, near Berlin, and ERWIN EHRHARDT, engineer, a subject of the Prince of Reuss, residing at S. W. 4 Askanisther Platz, Berlin, Germany, have invented a certain new and useful Improvement in Apparatus for Perforating the Type-Bands for Automatic Telegraph Transmitting Apparatus or the Like, of which the following is a full, clear, concise, and exact description.

Our invention relates to a perforating apparatus serving for the production of perforated type-bands, such as are used in particular for rapid telegraphy with automatic telegraphic transmitters. These perforating apparatus operate in such manner that a set 15 of perforating-punches over which the paper band is drawn with a step-by-step motion are operated upon by a keyboard and suitable intermediate mechanism in such manner that the separate punches thereof are forced through 20 the paper in certain combinations corresponding to the letter or symbol to be produced. Generally the said combinations are previously prepared in groups in the apparatus in the form of suitable mechanically or electrically 25 acting elements, so that merely by a pressure on a corresponding key the desired combination is brought into action as a whole, so as to produce a complete group of perforations representing the desired letter or symbol.

According to the present invention the combinations of mechanical elements corresponding to the groups of perforations are arranged in the form of groups of pins situated in parallel rows upon the periphery of a continuously-revolving drum or equivalent device 35 and are made at a certain point of the path through which they travel to coöperate with the set of perforating-punches, so that according to the position of the pin-drum at the moment of coöperation a certain group of pins comes into action, so as to produce a corre-

sponding combination of holes in the type-band.

The advantages of this invention are that an auxiliary power can be applied effectively 50 for the actual punching operation and for actuating the punching mechanism, that the speed of working determined by the most rapid manipulation by hand can be easily attained, and that it enables an effective and 55 strong construction based on mechanical principles to be employed that satisfies all practical requirements.

In the accompanying drawings is shown the construction of apparatus preferably employed for carrying out the invention.

Figure 1 shows a part front view and part vertical section of the complete apparatus. Fig. 2 shows a side view of its upper part; Fig. 3, a sectional plan on line I I, Fig. 2. 65 Fig. 4 shows a part section with the stopping and releasing devices in a different position from that at Fig. 1, and Fig. 5 a transverse sectional side view of the parts shown in Fig. 4.

w is the pin-drum, and *p* the punch-frame, 70 which is here shown immediately opposite the pin-drum. The latter revolves with the vertical spindle *b* and receives motion through the bevel-wheels *r' r²* from the shaft *c*, driven by an external source of power—as, for instance, a small electric motor. The punch-frame *p* is mounted on lever *n n* by means of two lateral projections *p'*, so as to be capable of rocking thereon, and is generally held by the stop *q* and spring *q'* in a certain normal 75 position. The levers *n n* are pivotally mounted on a spindle *u* and are generally drawn by springs *s'* against the stops *s*.

In the front part of the punch-frame *p* is arranged the row of punches, Figs. 2 and 3, 85 the one end surface of which is presented to the pin-drum, while the other end surface is presented to the paper band led through the slot *d* of the frame *p*. The punches are separately movable and are acted upon by springs 90 *f*, engaging with grooves, so as to hold these normally in the position shown. In conse-

quence of this arrangement when the punch-frame p is pressed against the pin-drum the separate punches in coming in contact with the pin which may happen to be opposite them 5 will be pressed through the paper band, so that a group of holes is formed corresponding to the particular combination of pins that act upon the punches. As all the requisite combinations of pins are provided on the drum, 10 it is only necessary to effect the said pressing of the punches against the pin-drum at the moment when a certain pin group is presented to the punches for producing the required type-perforations. The last-named operation 15 is in the present case performed by means of an arrangement of differential gear consisting of bevel-wheels r' , r^5 , and r^4 and two revolving arms o' and o^2 , which operate in conjunction with a number of stops h , arranged in a 20 circle and corresponding in number to the number of pin groups on the drum, the action being as follows: The levers n , carrying the punch-frame p and which, as above stated, can rock on u , are connected by short links m 25 with a loop-shaped bar k , Fig. 1, mounted loose on the spindle b , the lower limb of which bar forms a bearing for the axis i of the middle wheel r^5 . It will be evident from this arrangement that the turning of the looped bar k in a certain direction will cause the punch-frame to approach the pin-drum w . As the punch-frame is normally held in position relatively to the pin-drum (shown at Figs. 2 and 3) and which is determined by the stop q , it 30 follows that the looped bar k and axis i also have a correspondingly-limited normal position. 35

Of the three wheels the upper one, r' , is fixed on the spindle b of the pin-drum and 40 transmits the motion it receives from the bevel-wheel r^2 , by means of bevel-wheel r^5 , to the lower wheel r^4 , which is mounted loose on the hub of a bevel-wheel r^3 , that is mounted loose on spindle b and is in gear with the bevel-wheel r^2 . The two wheels r^4 and r^3 , which in 45 consequence of the chosen ratio of transmission revolve in the same direction and at the same speed as the pin-drum, carry, respectively, an arm o' and o^2 fixed thereon, such 50 arms being arranged at a slight angle to each other, as shown at Fig. 3, o' being in advance of o^2 . If now a certain obstacle is opposed to the arm o' on its rotation round spindle b , it will be seen that in consequence of wheel r^4 55 being stopped wheel r^3 and its spindle will be shifted round somewhat, and in carrying the looped bar k round with them the punch-frame will be moved by k and n toward the pin-drum against the action of spring s' . On 60 the arm o' being released the punch-frame will of course at once be made to spring back, together with the looped bar k and wheel r^5 , into their original position by the action of springs s' .

65 The arresting of arm o' for the purpose of

bringing the punch-frame against the pin-drum, so as to effect the perforation of the paper by a certain group of punches, is effected by causing one of the stops h , arranged in a circle, to be brought into the position 70 shown in Fig. 4 by means of a corresponding key t , in which position the stop will lie in the path of arm o' . According to the position of the stop h , which is thus actuated, the resulting motion of the punch-frame will occur 75 at a definite period of the revolution of the pin-drum, and consequently a correspondingly definite group of pins will be made to act upon the punches for perforating the paper. The forward motion of the punch-frame 80 against the pin-drum must of course be limited, and consequently the time during which the arm o' is arrested must also be accurately determined. The arm o^2 serves for this purpose, and, as above stated, it is situated at a 85 definite angle to the arm o' in the backward direction, as shown in Fig. 3, and it is so formed with an incline on its front operative side, as shown in Fig. 5, that when a stop h has arrested the arm o' arm o^2 in continuing to 90 move forward bears with its incline upon a corresponding incline on the stop, and in thereby pushing the stop upward causes it to release the arm o' and also to move out of its own path. The arm o' , as above described, is at once 95 made to spring back into its original position relatively to arm o^2 , together with the punch-plate and other intermediate devices, by means of the springs s' .

Briefly stated, therefore, the complete operation is as follows: On the depression of a certain key t the corresponding stop h arrests the revolving arm o' , thereby causing the corresponding group of pins on the pin-drum to operate certain of the punches, so as to perforate the paper during the forward motion of the punch-frame, and immediately afterward the advancing arm o^2 liberates arm o' from the stop, causing it and the parts connected therewith to reassume their original positions. The forward feed of the paper is effected automatically by means of a ratchet-wheel g , Figs. 2 and 3, and a spring-pawl j , carried by the frame, the wheel g being mounted on the same spindle with two pin-wheels $j' j''$, that are engaged with two lateral rows 110 of perforations on the paper band, so that at each forward motion of the punch-frame the ratchet-wheel g and wheels j' are turned forward one tooth, so as to feed forward the paper just before the punching is effected. In the construction shown on the drawings there is also provided an arrangement for producing on the paper a corresponding type impression at the same time that it is perforated, 115 so that the perforated message can be directly read from it. The upper part w' of the pin-drum w is for this purpose provided with projecting types round its periphery corresponding to the respective pin groups 120 125 130

below. The diameter of w' is such that on the forward motion of the punch-frame the type corresponding to the pin group that then comes into action is impressed upon the edge 5 of the paper band beyond the perforations. The supply of ink to the type can be effected in any known manner. As the contact of the paper band with the printing-type lasts a certain, though very short, time, while the type 10 continue their rapid rotation, the impression would become blurred if the paper remained stationary during the impression. To prevent this and also to insure the proper contact of the pins with the punches, the punch-frame is, as previously stated, mounted on the levers n , so that it can rock thereon, and a toothed wheel z , revolving with the drum w w' , and which at the required moment engages with a pin z' on the punch-frame, 15 causes the latter to perform a slight turning motion against the action of spring q' , so that by suitably proportioning the toothed wheel the paper band during the time of receiving the perforations and impression has 20 a slight forward motion imparted to it at the same speed as the pins and type.

What we claim as our invention, and desire to secure by Letters Patent, is—

1. The combination, in an apparatus for perforating type-bands, of a revolving drum carrying groups of pins on its periphery with a punch-frame pivotally movable opposite the pin-carrying drum and a differential gear on the axis of the drum whereby the punch-frame 35 is caused to move toward the pin-carrying drum, as and for the purpose set forth.

2. The combination, in an apparatus for perforating type-bands, of a revolving drum carrying groups of pins on its periphery, with a punch-frame pivotally mounted on lever-arms, the latter carrying the bearing of a wheel of the differential gear whereby said wheel causes the punch-frame to move toward the pin-carrying drum, as and for the purpose set forth.

45 3. The combination, in an apparatus for perforating type-bands, of a revolving drum carrying groups of pins on its periphery, a punch-frame pivotally mounted on lever-arms, with a differential gear connected to the main shaft 50 and to the axis of the drum, a pair of arms revolving with the axis of the drum over a series of stops arranged in a circle, as and for the purpose set forth.

4. The combination, in an apparatus for perforating type-bands, with a revolving drum carrying groups of pins on its periphery, of

a punch-frame pivotally mounted on lever-arms, a differential gear on the axis of the drum, a pair of arms revolving therewith over a series of stops actuated by finger-keys so as 60 to bring one or other thereof into the path of the leading arm to arrest it, as and for the purpose set forth.

5. The combination, in an apparatus for perforating type-bands, with a revolving drum 65 carrying groups of pins on its periphery, of a punch-frame pivotally mounted on lever-arms, a differential gear on the axis of the drum, a pair of arms displaced at an angle to each other, said arms revolving over a series 70 of stops actuated by finger-keys so as to bring the stop corresponding to the desired letter into the path of the leading arm to arrest it, the stop being disengaged therefrom immediately after by the following arm, as and 75 for the purpose set forth.

6. The combination, in an apparatus for perforating type-bands, with a revolving drum carrying groups of pins on its periphery, of a punch-frame pivotally mounted opposite 80 the pin-carrying drum and a differential gear on the axis of said drum, the gear-wheels being connected respectively to the main shaft, to a pair of arms revolving over a series of stops and to the loop-shaped bar k controlling 85 the punch-frame-carrying levers so as to cause said punch-frame to move toward the pin-carrying drum, as and for the purpose set forth.

7. The combination, in an apparatus for perforating type-bands, with a drum carrying 90 groups of pins on its periphery, of a punch-frame pivotally mounted opposite the pin-carrying drum, and a type-ring revolving with the drum, as and for the purpose set forth.

8. The combination, in an apparatus for perforating type-bands, with a drum carrying 95 groups of pins on its periphery, of a punch-frame pivotally mounted opposite the pin-carrying drum, a type-ring and a toothed wheel 100 revolving with the drum, the toothed wheel engaging with the punch-frame when the latter is pressed against the pin-carrying drum, as and for the purpose set forth.

In witness whereof we hereunto subscribe our names this 10th day of February, A. D. 105 1904.

ADOLF FRANKE.
ERWIN EHRHARDT.
